United States Patent

Des. 236,406
Patented Aug. 26, 1975

236,406

CANISTER WITH LID OR SIMILAR ARTICLE

Walter B. Achenbach, Toledo, Ohio, assignor to Owens-Illinois, Inc., Toledo, Ohio

Filed Nov. 30, 1973, Ser. No. 420,524

Term of patent 14 years

Int. Cl. D7—01

U.S. Cl. D7—17

FIG. 1

FIG. 2

FIG. 3

FIG. 1 is a side elevational view of a canister with lid or similar article showing my new design;

FIG. 2 is a top plan view thereof;

FIG. 3 is a bottom view thereof.

I claim:

The ornamental design for a canister with lid or similar article, as shown and described.
